UNITED STATES PATENT OFFICE.

ALBERT C. BELL, OF CHICAGO, ILLINOIS

FOLDING SOFA-BED.

1,101,988.

specification of Letters Patent. Patented June 30, 1914.

Application filed January 19, 1909. Serial No. 473,...

to whom it may concern:

Be it known that I, ALBERT C. BELL, a citizen of the United States, residing at Chicago, in the county of Cook and State of Illinois, have invented certain new and useful Improvements in Folding Sofa-Beds, of which the following is a full, clear, concise, and exact description, reference being had to the accompanying drawings, forming a part of this specification.

My invention relates to folding sofa beds, and has for its object to provide such a construction that the bed when opened up shall have a greater width than has heretofore been found practicable.

In the past, in connection with sofa beds of this class, it has been found impracticable to secure a width of bed greater than that known in the art as a "three-quarter" bed without using an excessive width of sofa seat. By my invention, I secure a full-width double bed without, however, increasing the width of the sofa seat beyond that usually employed.

A further object of my invention is to produce a folding sofa bed which shall be readily separable for shipping purposes, the mechanism associated with the sofa seat being so constructed as to not interfere in any degree with taking the sofa bed apart.

A further object of my invention is to provide a counterbalancing means by which the weight of the revolvable seat is practically balanced at all times whether in the sofa position or in the bed position. This balance is of such a nature that for either of these positions the weight of the seat and the parts carried thereby is slightly in excess of the counterbalancing means, which, however, exceeds the effect of this weight when the seat is in an intermediate position during the opening of the bed.

A further advantage secured by my invention consists in using practically all of the space between the under side of the seat and the floor as a compartment for bedding when the structure is in the sofa position. Furthermore, by my construction, the height of the sofa seat may be made to accord with that commonly used in the construction of sofas, divans, &c., without in any way sacrificing the amount of space available in the bedding compartment.

By my combination, I further provide that the sofa seat shall be positively supported in its four corners when the seat is in

position to be used as a sofa, and that such seat is also supported at four points when revolved to the bed position.

The several drawings illustrating my invention are as follows:

Figure 1 is a perspective view of my sofa bed in its sofa position; Fig. 2 is a perspective view of the sofa bed with the seat revolved and the bed portion opened up; Figs. 3, 4, 5 and 6 are end views of the sofa bed with the end toward the observer removed, these views showing the several positions of the seat that are assumed during the rotation of the seat from its sofa position, shown in Fig. 3, to its bed position, shown in Fig. 6; Fig. 7 is a detail view of a part of the back rail of the seat, showing the coöperation of one of the end supports of the seat with a supporting bracket carried by the end of the sofa bed; Fig. 8 is a detail sectional view taken along the dotted line 8—8 in Fig. 3; Fig. 9 is a detail sectional view taken along the dotted line 9—9 in Fig. 3; Fig. 10 is a detail sectional view taken along the dotted line 10—10 in Fig. 3; and Fig. 11 is a detail sectional view taken along the dotted line 11—11 in Fig. 5.

Similar numerals refer to similar parts throughout the several views.

As shown in Figs. 1 and 2, the sofa bed consists in a back portion 12, to which at either end are secured the ends of the sofa 13 and 13^a. Between the ends 13 and 13^a, and supported therefrom, is placed a revolvable seat 14. The seat 14 supports from its under side a bed frame 15, which carries a spring 16 of well known type.

As shown in Figs. 3, 4, 5 and 6, the end 13 is removed from the rest of the sofa structure, without, however, removing the several parts secured to the end which are employed to support the end of the seat toward the observer. These parts carried by the end 13, but dissociated therefrom in these figures, consist in, first, an angle iron 17, upon which one corner of the seat rests. This corner of the seat has secured on its under side a block 18 and a bent iron 19 by which, as the seat is rotated in a manner to be explained, the back edge is positively guided and supported until the pivots of the seat have been moved to their uppermost position. A second member supported from the end 13 consists in a clip 20 adapted to engage a bent bar 21 secured to the end of the seat. The coöperation of these parts

positively supports the front edge of the seat at the end toward the observer when the seat is in its sofa position. A third member supported by the end 13 consists in 5 a clip 22 similar to the clip 20, this clip 22 serving, as shown in Fig. 6, to engage the bent bar 21 when the seat is in its bed position, and to thus positively support the end of the seat for such position. A fourth 10 member supported by the end 13 consists in a plate 23 which carries a pivot 24 upon which a bell crank 25 is rotatably mounted. The upper arm of the bell crank 25 carries at 26 a pin adapted to engage a bracket 27 15 secured to the end of the sofa seat. The lower end of the bell crank 25 is engaged by a spring 28, the other end of which is secured to an adjustable bolt 29 fastened to the back of the sofa bed. It is to be understood 20 that the structure just described in Figs. 3 to 6, inclusive, is duplicated at the other end of the seat. As a result of this construction, when it is desired to rotate the seat from its sofa position to its bed position, the operator takes hold of the under 25 edge of the front board 30 of the seat and raises the same. The relation of the spring 28 and the lever arms of the bell crank 25 is such that the weight of the seat is nearly balanced 30 for this condition, as a result of which but little effort is required to lift the seat and clear the bars 21 from the clips 20 fastened to the ends of the sofa bed. The seat is first lifted as shown in Fig. 4, and 35 the rotation is continued until the position shown in Fig. 5 is assumed, at which time the supporting irons 19 are freed from the supporting angles 17, leaving the seat and parts carried thereby free to rotate on the 40 pivots 26. At this time the pivots 26 are practically over the pivots 24, while the springs 28 still have small effective lever arms tending to rotate the bell cranks 25 around to the left upon the pivots 24. This 45 rotation is not permitted, however, since the bell cranks 25 at this time engage pins 31 secured in the plates 23. The pivots 26 are therefore held practically rigid and the seat is rotated around to the right until the pins 50 32 engage the sides of the bell cranks 25, from which time the rotation, instead of being about the pivots 26, is transferred to the pivots 24, with the result that the front board 30 of the seat is brought well back 55 against the upholstery 12^a of the back of the sofa bed. In this position the bar 21 engages the clip 22, which prevents further rotation of the seat. The legs 33 pivoted to the framework 14^a of the seat are then rotated 60 to a position to support what is now the front edge of the seat.

It is to be observed in connection with the operation described above that the main pivots 26 of the seat are moved upward and 65 forward as the seat is rotated from its sofa

position to its bed position, which is just the condition required to give a maximum amount of clearance between the floor and the upholstery of the back. As a result of this construction, I am able to utilize practically all of the space beneath the seat without striking the floor or the upholstery of the back as the seat is rotated.

The bed frame 15 consists in three sections 15^a, 15^b and 15^c pivoted together and adapted 70 to fold up into the position indicated in Figs. 3 to 6, inclusive, the space between these sections when folded up being designed to accommodate the bedding. After the seat has been rotated to the position indicated in Fig. 6, the spring catch 34 is pushed back and the sections 15^c and 15^b are moved upward and to the left until they occupy the position indicated in Fig. 2. A leg 35 is pivoted at 36 to each section 15^c of the 80 bed frame, and is so connected by a link 37 to the section 15^b that when the sections 15^c and 15^b are opened up to the position indicated in Fig. 2, the legs 35 are automatically moved to positions to support the section 15^c 85 in practically the same plane as the section 15^a. The section 15^a is rigidly supported from the framework 14^a of the seat by means of the posts 38 and the front board 30.

When it is desired to return the seat to 90 its sofa position, the operator raises the outer section 15^c of the bed frame and moves it to the position indicated in Fig. 6, the catch 34 being so designed as to automatically engage such section 15^c and retain it 100 in its folded position. The legs 35 are by this operation automatically moved to the position indicated in Fig. 6. The engaging members of the sections 15^a, 15^b and 15^c are so constructed at their pivotal connections that the sections 15^c and 15^b cannot be moved in folding the bed further than indicated in Fig. 6. The conformation of these 105 pivotal joints is such also that when the sections are opened up to form a practically continuous bed frame, the sections 15^c and 15^b cannot be moved beyond their horizontal position, for which position they, together with the section 15^a, constitute practically a 110 continuous horizontal structure.

After the sections have been moved to the 115 positions indicated in Fig. 6, the legs 33 are folded so as to lie longitudinally of the seat 14, and the seat and parts carried thereby are rotated first upon the pivots 24 until the bell cranks 25 engage the pins 31, and then upon the pivots 26 until the stops 39 engage the under side of the board 40 located along the lower face of the upholstery 12^a. When in this position, a slight push serves to move 120 the seat and parts carried thereby to the rear and downward until the bars 21 engage the clips 20 and the irons 19 rest upon the angles 17.

As shown in Fig. 7, the stops 39 and the 130

irons 19 are so disposed relatively to each other that there is no interference between the stops 39 and the angles 17.

The nature of the engagement between the bars 21 and the clips 20 is shown in detail in Figs. 9 and 10.

The ends 13—13^a of the sofa bed are secured to the back 12 by means of bolts and wing nuts 41, as indicated in Fig. 8, by removing which the ends and back are readily separated from each other. This construction is provided in order that the sofa bed may be taken to pieces or "knocked down" to facilitate shipment. This process is facilitated by the construction of the supporting pivots and brackets, as indicated in Fig. 11. The pivots 26 secured in the bell cranks 25 are straight, and may be readily withdrawn from the brackets 27 secured to the framework 14^a of the seat. When it is desired to take the sofa bed apart, the seat is rotated to the position shown in Fig. 5. The bolts 41 at each end are then withdrawn, and the ends are removed one after another. As each end is removed, the pivot 26 carried thereby is readily withdrawn from the corresponding bracket 27 without requiring any special operation or disengagement of the parts. It is to be observed that displacement of the bell crank 25 relatively to the corresponding bracket 27 is prevented for either of the operative positions of the seat by the engagement of the bars 21 with either the clips 20 or the clips 22, which engagement serves to rigidly secure the ends of the sofa bed to the seat frame.

As shown in Fig. 11, the pivots 24 are rigidly secured to the plates 23, and are provided with heads to retain the bell cranks 25 in operative position upon such pivots.

The bolts 29 are adjustable in order that the tension of the springs 28 may be brought to the point required to properly balance the seat 14 and parts carried thereby.

While I have shown my invention in the particular embodiment herein described, I do not, however, limit myself to this construction, but desire to claim broadly any equivalent construction that will suggest itself to those skilled in the art.

What I claim is:

1. In a folding sofa bed, the combination of a frame, a rotary seat, folding bed sections secured to the under side of the seat, and supporting links pivoted to the seat and the frame and extending rearwardly from the frame pivots when the seat is in its seat position and vertically when the seat is in its rotating position.

2. In a folding sofa bed, the combination of a frame, a rotary seat, and links pivoted to the frame for pivotally supporting the seat, such links so disposed that the seat

pivots are practically over the frame pivots when the seat is in its rotating position and that such seat pivots are to the rear and practically in line with the frame pivots horizontally when the seat is in its sofa position.

3. In a sofa bed, the combination of a frame, a rotary seat, folding bed sections forming a clothes compartment under the seat and revoluble therewith, and links pivoted to the seat and to the frame to increase the clearance between the seat pivots and the floor and also between such pivots and the back of the sofa bed before rotating the seat from its seat to its bed position.

4. In a folding sofa bed, the combination of a frame, a rotary seat, links for pivotally supporting the seat, and devices pivotally connecting the links to the seat and frame in such a position that when the seat is moved to its rotating position the distance between the seat pivots and the floor and the distance between the seat pivots and the back of the sofa bed are increased by an amount substantially equal to the length of the links.

5. In a folding sofa bed, the combination of a rotary seat, a folding bed frame carried by the seat and consisting of three sections, the first one of the bed frame sections being secured to the under side of the seat and adapted to pivotally support a second of such sections, such second section adapted to pivotally support the third section, a leg pivoted to the third section and a link connecting the leg to the second section, such link serving to move the leg to a position to support the bed frame when the bed frame sections are opened to their bed position.

6. In a folding sofa bed the combination of a rotary seat, a supporting frame, a plurality of bed frame sections hinged together to fold under the seat, a leg pivoted to one of said bed sections to support said section, and a member connecting said leg with a part of the structure relatively to which said supported section rotates, said member serving to move the leg to supporting position when said section is rotated.

7. In combination, a rotary seat, a folding bed frame comprising a plurality of sections pivoted together, a leg pivoted to the uppermost section to support the bed frame from the floor, and a link connecting such leg with another of said bed sections, said link serving to move the leg to supporting position upon the floor when the bed frame is rotated to its bed position.

8. In a folding sofa bed, the combination of a rotary seat, a supporting frame, a plurality of bed frame sections hinged together to fold under the seat, a leg pivoted to the outermost of said bed sections to support the same, and a link connecting said leg

with a part of the structure relatively to which said outermost section rotates, said link serving to move the leg to supporting position when said outermost section is rotated.

9. In a folding sofa bed, the combination of a rotary seat, a supporting frame, a plurality of bed frame sections hinged together to fold under the seat, a leg connected to 10 one of said bed sections to support said sec-

tion, and mechanism connected with the leg for automatically moving said leg to supporting position when said section is moved to its bed position.

In witness whereof, I hereunto subscribe 11 my name this 9th day of January, 1909.

ALBERT C. BELL.

Witnesses:

LEONARD W. NOVANDER,
A. A. THOMAS.

with a part of the structure relatively to which said outermost section rotates, said link serving to move the leg to supporting position when said outermost section is rotated.

9. In a folding sofa bed, the combination of a rotary seat, a supporting frame, a plurality of bed frame sections hinged together to fold under the seat, a leg connected to one of said bed sections to support said sec-

tion, and mechanism connected with the leg for automatically moving said leg to supporting position when said section is moved to its bed position.

In witness whereof, I hereunto subscribe my name this 9th day of January, 1909.
